UNITED STATES PATENT OFFICE.

FRED AUGUST SCHMITZ, OF YOUNGSTOWN, OHIO, ASSIGNOR TO THE GENERAL FIRE-PROOFING COMPANY, OF YOUNGSTOWN, OHIO, A CORPORATION OF OHIO.

EDGE CONSTRUCTION FOR FURNITURE TOPS.

Application filed February 13, 1922. Serial No. 536,244.

To all whom it may concern:

Be it known that I, FRED A. SCHMITZ, citizen of the United States, residing at Youngstown, in the county of Mahoning and State of Ohio, have invented certain new and useful Improvements in Edge Constructions for Furniture Tops, of which the following is a specification.

This invention relates to a novel edge 10 construction for desk tops, table tops, seats and like articles of furniture.

In the construction of metal furniture, particularly office furniture, it is preferable to provide the top or exposed surface there- 15 of with a covering of material that will not easily scratch or mar and at the same time be more comfortable to the sense of touch. That is to say, it is desirable to make the cover or top facing of articles 20 of furniture of the type set forth of some material other than metal which will possess a certain degree of softness to deaden the resonance of metal, while at the same time providing a surface which feels comfortable 25 to the hand and also produces a satisfactory surface for writing or other like uses. Tops entirely of wood have been used for desks, but, as it is desirable to use metal throughout as far as possible the present construction 30 contemplates a sheet metal top having a novel edge and corner construction whereby linoleum or the like may be used as the covering for the metal thereby obviating the disadvantages incident to an all metal surface 35 above pointed out.

A further and more specific object of the invention is to provide a simple and practical construction that will reliably hold the edges of the linoleum to prevent curling up or roughing thereof where it is subjected to excessive wear.

With the above and other objects in view which will more readily appear as the nature of the invention is better understood the 45 same consists in the novel construction, combination and arrangement of parts herein-after more fully described, illustrated and claimed.

A preferred and practical embodiment of 50 the invention is shown in the accompanying drawings, in which:—

Figure 1 is a perspective view of a corner of the improved top construction.

Figure 2 is a cross-sectional view taken 55 on the line 2—2 of Figure 1.

Figure 3 is a sectional view taken on the line 3—3 of Fig. 2 showing the under face of the top.

Similar reference characters designate corresponding parts throughout the several 60 figures of the drawings.

According to the present invention it is proposed to provide a metallic top body 1 consisting of the wall 2 and depending side flanges 3 which may be inturned as indicated at 4 to provide a smooth finished and reinforced lower corner 5. The upper edge portion of the upper wall 2 adjacent the flange 3 is provided with a depressed seat 6 extending throughout the length of the edge of the top wall and intended to accommodate the lower anchoring flange 7 of the bead strip B. When this bead strip is placed in position the upper surface of its flange 7 will lie flush with the face of the wall 2 while the other flange 8 which constitutes a binding flange extends upwardly to provide a seat for the cover C. The said bead strip may be made of copper, brass, Monel metal, stainless steel or like material and the anchoring flange 7 is bolted or otherwise secured in the seat 6 by any suitable fastening means, such for example as the bolts 10 whose heads are counter-sunk in the flange while the shanks 85 project through the bottom wall of the seat to receive the nuts 11. As shown in Fig. 3 these nuts may be positioned so as to lock against the inside of the flange 3 to prevent displacement after the cover C has 90 been placed in position over the upper wall of the body 1.

Also, by the above arrangement the heads of the bolt are concealed by the edges of the cover which may be a sheet of linoleum 95 or the like that may be glued, cemented or otherwise secured to the wall 2 of the body 1. The edge portions of the cover however, lie within the angle of the bead strip so that the binding flange 8 constitutes an 100 ornamental as well as practical binding edge for the linoleum. The upper edge 9 of the binding flange or bead may be worked over the edge of the linoleum in such a way as to hook over and protect the 105 same as well as insure its being firmly anchored or held in place at the edges.

From the foregoing it will be apparent that the novel and distinctive feature of the present invention is the provision of a 110

metallic table top having a suitable covering held to the top at the edges by a novel beading that is securely anchored to the metallic top and in turn is worked or flanged over the edge of the linoleum to hold it in place.

Without further description it is thought that the features and advantages of the present improvement will be readily apparent to those skilled in the art and it will of course be understood that changes in the form, proportion and minor details of construction may be resorted to without departing from the spirit of the invention or scope of the appended claims.

I claim:

1. An edge construction for furniture tops including a top body comprising a flat upper surface and an angularly disposed 20 side flange, a bead strip of angular cross section having the horizontal flange thereof secured to the flat surface of the top body at the upper edge of the flange and exposing the latter, and a cover applied to 25 the flat surface of the top body and having its edge portion overlying the horizontal flange of the bead strip.

2. In an edge construction for furniture

tops, a top body having depending side flanges, and a seat formed adjacent the edge 30 of the body at the top of the flanges, an angular bead strip having its horizontal flange portion arranged within said seat and its vertical flange projecting upwardly in the plane of the side flange above which it is positioned, and a covering for said top body having its edge portion overlying the horizontal flange of said bead and embraced by the vertical flange thereof.

3. In an edge construction for metal 40 furniture tops, a top body having depending flanges and a depressed seat formed at the upper edge of the flanges, said seat being provided with spaced openings, an angular bead strip consisting of anchoring 45 and binding flanges, fastenings for piercing the anchoring flange of the bead strip and also projecting through the openings in the seat of the table top, a covering sheet for the top body having its edge portion overlying the anchoring flange of the strip and lying behind and beneath the binding flange 50 thereof.

In testimony whereof I hereunto affix my signature.

FRED AUGUST SCHMITZ.
